UNITED STATES PATENT OFFICE.

FRITZ ALDENDORFF, OF WILMERSDORF, NEAR BERLIN, GERMANY, ASSIGNOR OF ONE-
FOURTH TO PAUL KOLISCH, OF NEW YORK, N. Y.

AUTOMATIC SWITCHING SYSTEM.

Application filed January 29, 1923, Serial No. 615,627, and in Germany February 2, 1922.

This invention relates in general to automatic switches and telephone switching systems and more particularly to systems in which novel types of selectors or switches are employed whose movable contact can be set onto any contact or set of contacts in a contact bank with extraordinary rapidity. This object is accomplished by employing a brush carrier upon which a force is continually exerted for the purpose of moving same, and an arresting means for holding the brushes in an initial position against the action of said power and for positively stopping the power-driven brushes on any desired bank contact is employed. The arresting means may consist of two conducting parts in contact with each other, one of which is a semi-conductor and one of which is fixed to the brush carrier while the other is held stationary, electric circuits being arranged to co-operate with said conducting parts so as to cause them to adhere firmly to each other at the right moments. The semi-conductor is a material of high electric resistance such as the slate used by lithographers and which is found in large quantities near Solenhofen in Germany. Instead of the Solenhofen slate, agate may be employed.

A feature of the invention is a selector with bank contacts, wipers cooperating with the bank contacts and a wiper carrier whose movements are controlled by currents that affect a part moving together with the wiper carrier and another part continually bearing against the first part. The currents controlling the movements of the wiper carrier are preferably sent through the part that moves together with the wiper carrier and the part bearing against the said first part. The wiper carrier is preferably moved by a continuously acting force and stopped by currents sent through a semi-conductor contacting with a part belonging to, or moving with, the wiper carrier and through the bank contacts and wipers of the switch. When the switch is used as a finder the controlling or stopping currents are sent through the semi-conductor, a wiper and a bank contact of the switch to which a potential is applied by an element belonging to a calling line or trunk. When the switch is used as a group selector, the controlling currents are sent through the semi-conductor, a wiper and group designating bank contacts of the selector. The wiper

carrier, after being driven up to the desired bank contact group, is preferably driven further in a continuous movement, until the wipers are stopped on a free trunk by a current sent through the semi-conductor, a wiper of the switch and a bank contact associated with the free trunk. When the switch is used as a connector or final selector, the controlling current is sent through the semi-conductor, a wiper and group designating contacts, and then through line designating contacts instead of the group designating contacts.

In order to ensure that an intimate contact is maintained between all parts of the semi-conductor and the surface of the part that moves relatively thereto, a yielding connection is preferably provided between the wiper carrier and the part bearing against the semi-conductor.

The wiper carrier or propelled member of the switch is preferably driven by a tensioned spring. When the switch is used as a numerical selector, the propelling force is controlled by applying potential to one bank contact of the switch after another.

In the group selector stopping bank contacts are provided at the end of each group of bank contact sets for stopping a hunting wiper. A similar arrangement may be used in final selectors or connectors arranged for P. B. X. hunting.

The semi-conductor in the switch may be in the form of a cylinder surrounding the wiper carrying shaft, or it may be made in the form of a flat disk against which a metal disk rotated with the wiper-carrying-shaft bears.

A close-fitting split spring ring may be inserted between the semi-conductor cylinder and its bearing, and the ring may be arranged to drive a stopping pawl into the teeth of a disk fixed to the wiper carrier.

Another feature of the invention consists of means for treating or cleaning the surface of the semi-conductor which contacts with the metal part or disk attached to the wiper carrier or shaft of the switch or selector.

Other features of the invention will appear hereinafter in the drawing, description and claims.

The invention is shown in the drawing in which Figs. 1 and 2 are an elevation partly in section and a plan view of the new selector in which a semi-conductor is used for the

purpose of enabling the movable contacts of the switch to be moved round at a great speed and yet to be stopped instantaneously on reaching any desired set of contacts in the contact bank of the switch.

Figs. 3 and 4 show circuits that may be used in connection with the novel switch.

Figs. 5 and 6 are a plan view and vertical section respectively of a modified bearing 10 and arresting device for the switch shown in Figs. 1 and 2.

Fig. 7 is an elevation and

Fig. 8 a plan view of another modified switch in which the semi-conductor has the 15 form of a flat disk.

Fig. 9 is a diagrammatical vertical section of Fig. 7 in which the mechanical connection between the wiper carrier or shaft and the metal disk that contacts with the semi-conductor disk is more clearly shown.

Figs. 10, 11 and 12 show the circuits of a line finder, group selector and connector respectively of the type shown in Figs. 7, 8 and 9.

Fig. 13 illustrates a modification of the starting circuits for line finders which operate in general in the same manner as the starting circuits shown in Fig. 3.

Fig. 14 is an elevation of a device for treating or cleaning the surface of the semi-conductor which contacts with the metal disk connected to the shaft of the wiper.

Fig. 15 shows a detail of Fig. 14 and

Fig. 16 is a cross section through the brush of the cleaning device of Fig. 14.

Fig. 17 is a sectional view of a modified flexible mechanical connection between the contacting metal disk and the shaft of a switch of the type shown in Figs. 7 to 9.

In Fig. 1, 1, 2, 3 and 4 are four brushes which project out in two opposite directions from the rotary member of the switch. This rotary member consists of a toothed wheel 5 to which a pin or shaft 6 is fixed, a top rotary portion consisting of a sleeve 7 with a flange 8 made of a semi-conductor, a metallic core 9 with a flanged bottom portion 10, and of layers of packing material 11, 12, 13 and 14 between which the brushes 1, 2, 3 and 4 are embedded. The brushes 1, 2, 3 and 4 are insulated from the body of the switch and from each other by suitable layers of insulation. The toothed wheel 5 has holes 15 and 16 through which screws 17 and 18 are inserted which serve to hold all the parts 5, 6, 7, 8, 9, 10, 11, 12, 13, 14 of the rotor of the switch together. The sleeve 7 which is made of a semi-insulator is journaled in a bearing 19 that is designed so as to exert a certain pressure against the sleeve 7 so as to continually establish an intimate mechanical contact. The lower shaft 6 is journaled in a sleeve 20 which is combined with a housing 21 provided at the rear with a flange or lug 22 by which the housing 21 is screwed

fast to a rack or frame. A spiral spring or clock spring 23 is disposed in the housing 21, its one end being attached to the lower shaft 6 and its outer end being fixed to the housing. This spring is tensioned and tends to rotate the rotor with the brushes 1, 2, 3, 4 at a relatively high speed. The rotor is, however, held in its normal position by a detent 24, Fig. 2, adapted to swing around the pivot 25. The detent has an arrow-shaped end 26 with two oblique surfaces adapted to be engaged by the roll 27 of a rocker arm 29 whose upper end is acted upon by a spring 30. In the position shown in Fig. 2 the roll 27 engages with the upper oblique surface of the arrow-shaped end 26 of the detent 24 thus tending to swing the detent 24 round clockwise so that its left end 31 engages with a pin 32. The left end of the detent 24 has a cam surface 35 and a detaining tooth 36 which holds the toothed wheel 5 against rotation in the direction of the arrow 27. When a current impulse is sent through the magnet 38 this magnet attracts its armature 39 whereupon the propelling pawl 40 engages with a tooth of the wheel 5 and rotates it in the opposite direction to that of the arrow 27. The pin 32 fixed to the wheel 5 then rides up on the cam surface 35 and throws the detent 24 round in a counter-clockwise direction and causes the detaining tooth 36 to release the detaining pin 33 so that the wheel 5 is rotated by the spring 23, Fig. 1, in the direction of the arrow 37.

When the detent 24 is turned counter-clockwise its arrow-shaped end 26 is moved upward so that the roll 27 engages with the lower oblique surface of the head 26. The detent 24 is provided with a restoring arm 41 which is brought into the path of a restoring pin 42 when the detent is swung round counter-clockwise by the pin 32 as described. When the wheel 5 has rotated through a certain angle so that the holding pin 33 has travelled past the detaining tooth 36 the restoring pin 42 strikes against the inner end of the restoring arm 41 and restores the detent 24 into its normal position in which the roll 27 engages with the upper oblique surface of the arrow-shaped head 26 of the detent 24 as shown in Fig. 2. When the wheel 5 is restored to its normal position by further impulses sent through the magnet 38 the holding pin 33 slips over the top of the detaining tooth 36 and rotates the detent 24 through a small angle without causing the roll 27 to leave the upper oblique surface of the arrow-shaped end 26 of the detent 24. The moment the holding pin 33 slips down at the right hand side of the holding tooth 36, or more correctly speaking, the moment the holding tooth 36 slips up at the left hand side of the holding pin 33 the left hand end of the detent 130

24 enters into engagement with the release pin 32 and the parts will then have regained the position shown in Fig. 2.

The shaft 9 of the switch may be provided with a recess with which the spring 43 of an off-normal switch engages as long as the switch is in its normal position. The moment the switch leaves its normal position the spring 43 leaves the spring 44 and is caused to make contact with the spring 45.

The wipers 1, 2, 3 and 4 travel over bank contacts which are not shown in Figs. 1 and 2. The circuits of the switch are arranged so that the moment a wiper, as 1, strikes the contact of any desired contact set in the bank a current is caused to flow through the fixed metallic journal 19 the rotary sleeve 7 made of a semi-conductor and through the metallic core 9. The adhesive force which is then instantaneously set up between the fixed journal 19 and the rotary sleeve 7 causes the latter to stick in the bearing and the brushes 1, 2, 3 and 4 are then stopped on the particular set of bank contacts in question.

The switch may be used as a line finder, group selector or wanted line selector and the circuits illustrating these uses of the switch are shown in Figs. 3 and 4.

In Fig. 3, 100, 101 and 102 are subscribers' stations. Associated with each subscriber's line is a line relay 105, an auxiliary line relay 104 and a cut-off relay 103. The line relay 105 and the auxiliary line relay 104 can be replaced by a single marginal relay or by relays consisting of a semi-conductor sandwiched between two metal bodies. This applies also to many of the other relays shown in Figs. 3 and 4. L in Fig. 3 is a line finder and WS in Fig. 4 is a wanted line selector. Switches of the general type shown in Figs. 1 and 2 can be interposed between the line finders and the wanted line selectors and arranged to act as group selectors.

The operation of the circuits will now be described.

When a subscriber as 102 raises his receiver a current flows over his line from the positive pole of the battery through contacts 106, 106', 106'', of the line relays of the group to which the calling subscriber belongs and then through contact 107, line relay 105, contact 108 of the auxiliary line relay, contact 109 of the cut-off relay 103, subscriber's station 102, contact 110 of the cut-off relay 103, group relay 111 to the negative pole.

The line relay 105 closes a circuit for itself at its contact 113 and opens its contacts 107, 106, 114 while closing its contact 115. By the closure of 115 the wire 116 is connected to the auxiliary line relay 104. The starting relay 111, which is common to a group of subscribers, closes its contact 112. The finder starting current flows from the negative pole

through 112, starting wire 117, contact 118 of the off-normal switch of the line finder L, magnet 138, which corresponds to the magnet 38 of Fig. 2, to the positive pole. The magnet 138 thus receives an impulse and the rotor of the line finder is released so that the spring 23, Fig. 1, drives the wipers 121, 122, 123 round at a high speed over the bank contact sets of the line finder. The moment the switch leaves its normal position the contacts 124, 125, 126, 119, 127 of the off-normal switch of the line finder are closed and the contact 118 of this off-normal switch is opened. The closure of the contact 124 results in the energization of the auxiliary line relay 104 by a current which flows from the positive pole through 124, 116, 115, 130, 104, 119, 102, 110, 111. The auxiliary line relay deenergizes the main line relay 105 and thereby reconnects the positive pole through 106, 106', 106'' to the other main relays as 105', 105'' so that these other relays can be energized to send further calls through the starting wire 117, 117' to other line finders. It is thus seen that when a subscriber calls he starts a certain line finder and that other calls made by other subscribers each affects some other free line finder.

Through its contact 135 the auxiliary line relay applies the negative of the battery to a contact 136 in the bank of the finder. The moment the brush 120 reaches the contact 136 a current flows from the positive pole through the contact 152, metallic core 9', semi-conductor sleeve 7', fixed outer metallic sleeve 19', brush 120, 136, 135 to the negative pole and the adhesion set up between the fixed outer metallic sleeve 19' and the rotary semi-conductor sleeve 7' causes the brushes 120, 121, 122, 123 to stop on the bank contacts 136, 139, 150, 151 whereupon a current flows from the negative pole through a contact 153 of a slow-acting relay 154, Fig. 4 relay 155, contact 125, brush 123, bank contact 151, contact 156, cut-off relay 103 to the positive pole. The cut-off relay 103 disconnects the calling subscriber's line from the starting relay 111 and the auxiliary line relay 104 and the relay 155 connects the calling subscriber's line through its contacts 157, 158 to the impulse relay 159. The relay 155 also closes its contacts 160, 161, 162 and opens the contacts 163, 164. The closure of the contact 161 results in the energization of the relay 165 which opens its contact 152 and closes its contacts 166, 167, 168. The relay 165 closes a locking circuit for itself which extends from the positive pole through 168, 127 to the negative pole.

The impulse relay 159 is now energized by current flowing through the calling subscriber's line. It closes its contacts 200, 201, 202, 203 and opens its contact 204. The closure of the contact 200 results in the energization of the release relay 206 which

closes a locking circuit for itself that extends through 207, 206, resistance 208 to the positive pole of the battery. The release relay also closes a contact 209 and thus applies the negative pole to the core 210 of the selector and at the same time energizes the stepping magnet 213 to prepare the step-by-step movements of the brushes 214, 215, 216, 217 of the wanted line selector WS. Although the magnet 213 is energized to release the rotor of the switch this switch is for the moment kept in its normal position on account of the adhesive force set up between the semi-conductor sleeve 212 and the outer metallic sleeve 211. This adhesive force is set up by a current which flows from the negative pole through 209, metallic core 210, semi-conductor sleeve 212, outer metallic sleeve 211, brush 217, wires 218, contact 219 of relay 220, contact 202, resistance 221 to the positive pole. When the subscriber sends in his dialling impulses the positive pole of the battery is alternately disconnected from the wire 225 and the negative pole connected through 209 to the armature 227 is alternately disconnected from the wire 226. When the positive pole is disconnected from the wire 225 it is also disconnected from the contacts 230, 231 and at the same time the positive pole is connected through the resistance 222 and the contact 235 to the long contacts 232, 233 in the bank of a wanted line selector. When the positive pole is removed from the long contact 230 the current flowing through the metallic core 210 and through the semi-conductor sleeve 212 and the outer metallic sleeve is interrupted so that the adhesive force disappears and the spring 23, Fig. 1, swings the brushes 214, 215, 216, 217 round until the brush 217 encounters the long bank contact 232 when a current will flow from the positive pole of the battery through 222, 235, 232, 217, 211, 212, 210, 209 to the negative pole. When the calling subscriber's loop is again closed after an interruption of the same the contacts 202, 203 are closed and the negative pole is directly applied through 209, 203, 235 to 232 so as to short-circuit the current flowing through 211, 212, 210. The adhesive force between the semi-conductor sleeve and the outer metallic sleeve then disappears and the spring of the selector jerks the brushes forward until the wiper 217 lands upon the long contact 231 when a current will flow from the positive pole through 202, 219, 231, 217, 211, 212, 210, 209 to the negative pole and again stop the brushes. It is thus seen that the brushes 214, 215, 216, 217 are caused to execute two hops or steps at each oscillation of the armature of the impulse relay 159. The bank contacts passed over by the wipers when they execute two hops are arranged so as to lie in a corresponding group, say a tens group,

of bank contact. It will be supposed that the subscriber sends in one tens impulse so as to cause the wipers to skip round onto the long contact 231 and that he thereupon sends in further impulses by which the 70 wipers are stepped onto a particular set of bank contacts in the tens group.

During the pause which ensues between the tens and units dialling impulses the change-over relay 240, which was previously 75 energized by a circuit from the negative pole through 207, 240, 240² to the positive pole, is deenergized and a current flows from the negative pole through 207, 241, off-normal contact 242 to right hand winding of relay 220 to the positive pole. The relay 220 is thus energized and closes a locking circuit for itself at its contact 243 while disconnecting the wires 225, 226 from the contacts 230, 231 . . . 232, 233 and connecting 80 the wires 225, 226 to the wires 246, 247 which lead to bank contacts as 248, 249, 250, 251 by means of which the selector is set onto individual bank contact sets. At each oscillation of the armatures of the impulse 85 relay 159 the brush 217 will now be advanced by two steps as from 250 to 251 and from 251 to 252 in the same manner as explained in connection with the long contacts 230, 231 . . . 232, 233. 90

When the wipers have thus been set onto the bank contact set of a wanted line another pause ensues in which the contact 255 of the change-over relay 240 is closed and a current then flows from the negative pole through 95 255, 256, test relay 257, wiper 216, bank contact 260, cut-off relay of the wanted subscriber's line to the positive pole. The test relay 257 then closes its contacts 260', 261, 263, contact 263 switching on the ringing relay 264. When the wanted subscriber responds a ringing cut-off relay 265 is energized and this in turn energizes an auxiliary release relay 266. 100

At the end of the conversation the 110 switches are restored to their normal positions by impulses sent through their stepping magnets 138 and 213. The restoration of the line finder for example is accomplished by sending impulses alternately through the stepping magnet 138 and through the metallic core 9', the semi-conductor sleeve 7 and the outer metallic sleeve. The impulses sent through the core and the said sleeve perform the office of a holding 115 pawl during the restoration of the switch. 120

The negative pole is not reconnected through contact 153 of the slow relay 154 to the relay 155 before the latter is deenergized so that the interrupters 180, 181 will 125 be connected through 164, 163 and 166, 167 to the wires 182, 183.

The bearing consisting of the semi-conductor sleeve 7 and the bracket 19 in Fig. 1 may be modified as shown in Figs. 5 and 6. 130

- In these latter figures, 19' is a bracket, 9' a metallic core, 7' a semi-conductor sleeve, 300 a split spring sleeve inserted between the semi-conductor 7' and the bracket 19', 301 5 a toothed disk, 302 a detent adapted to swing round a pivot 303 projecting from the top surface of the bracket 19', 304 a spring that normally keeps the detent 302 out of the path of the teeth of the toothed disk 301. 10 The bracket 19' is provided with an arm 305 in whose outer end there is a hole through which extends a threaded pin 306 that is provided with an adjusting nut 307 and a lock nut 308. The split sleeve 300 is held 15 in a rotary normal position by means of a spring 309 connected at one end to an arm 310 projecting from the sleeve 300 and at the other end to the threaded pin 306. Current is conducted to the metallic core 9' by a 20 contact spring 311. The operation of this arresting device is as follows: When the switch is started the core 9' and the semi-conductor 7' revolve rapidly in the split 25 spring sleeve 300 and the moment of potential is applied to the core 9' and the sleeve 300 the latter adheres to the semi-conductor-sleeve 7' so that the sleeve 300 is carried around in the direction of the arrow against the action of the spring 309. The pin 320 30 immediately drives the detent 302 into a tooth of a toothed disk 301 so as to stop the wiper carrier or shaft.
- The operation of the modified starting circuits shown in Fig. 13 will now be explained. When a subscriber, say 400, raises his receiver, a current flows from the negative pole through contact 403 of the relay 404, which is common to a group of subscribers, contact 405 of the line relay 406 35 of the calling subscriber, line relay 406, contacts 407, 409 of the cut-off relay 408, limb 410 of the subscriber's line, subscriber's station 400, second limb 411 of the calling line, contact 412 of the cut-off relay to the 40 positive pole. The line relay 406 is immediately energized and closes its contacts 413, 414, while opening its contacts 405 and 416. By opening contact 405 and closing 413 the relay 406 changes its own energizing circuit 45 so as to receive current through the relay 417 (which is common to the group of subscribers) instead of through the contact 403. The starting relay 417 is energized and sends a starting impulse to a finder, this impulse flowing through 403 and contact 419. An 50 energizing current for the relay 404 also flows through the contact 418, but before this relay 404 is energized a starting current will have passed through the starting wire 420. 55 When the relay 404 is energized it disconnects the battery from the back contacts of all of the other line relays such as 406' of the other subscribers of the group so that for the moment no other line of relay can 60 be energized. An impulse is, however, im- 65 mediately sent back from the started finder, over the wire 421 and this impulse flows through the contact 414, lower winding of the cutoff relay 408 to the negative pole. The cutoff relay 408 is partly energized so as to move its light armatures 422 and 427 and close the contact 423, whereby a locking circuit for the relay 408 is established that extends from the negative pole through contact 423, contact 409, over the line of the 70 calling subscriber and back and finally through the armature contact 412 to the positive pole. By the operation of the light armature 422 the circuit of the line relay 406 is broken at 407. When the wiper of the started finder reaches the bank contact (not shown) connected to the wire 425 a comparatively strong current flows through this wire 425 and through 415 and the top winding of the cut-off relay 408, causing this 75 relay to be fully energized and to open its contacts 409, 412. 80
- When the line relay 406 is deenergized through the opening of the contact 407 the relay 417 is also deenergized to open the 85 circuit of the relay 404 at contact 418. Contact 419 of the relay 417 opens before contact 403 of relay 404 is closed and a false starting impulse is thereby prevented from flowing through the starting wire 420. 90
- When the relays 417 and 404 are deenergized a new starting impulse can be sent through the starting wire 420 by another subscriber, as for example 401, raising his receiver and thereby energizing his line relay 406. 100
- It is thus seen that each calling subscriber starts an idle finder practically at the same moment in which he sends in his call by the act of raising his receiver, and while the 105 wipers of a started finder are still travelling in search of a calling line, another finder may be started by a call from another line, the call from the first line being prevented from starting the second finder by its line 110 relay being rendered incapable of energizing the common relay 417 that sends starting impulses to the finders until its cut-off relay is deenergized. This cut-off relay can, however, only be deenergized by the calling subscriber replacing his receiver. The cut-off relay acts as a means for severing the normal relation between a calling line and the finder starting wire or circuit the moment a finder 115 has been started by the calling act of the calling line. 120
- In known finder starting arrangements for starting line finders one after the other, an interval of 1, 2 or more seconds generally elapses between the starting of one finder and the next when two subscribers call at practically the same moment. If three or more subscribers call at the same time the interval will often be so long that the third subscriber that calls will generally have com- 125 130

inenced dialling long before a finder has connected his line to a selector. By the novel starting arrangements shown in Figs. 3 and 13 these intervals are reduced to fractions 5 of seconds and the danger of premature dialling on the part of calling subscribers is thus practically eliminated.

Where line finders of known types that operate comparatively slowly are used, the 10 novel finder starting arrangement will aid very considerably in preventing premature dialling. But where the exceedingly quick-acting finders shown herein are employed a simpler finder starting arrangement of the 15 kind shown in Fig. 10 will generally be found to suffice. This will be fully described hereinafter.

The type of switch used in the system shown in Figs. 10, 11 and 12 is illustrated in 20 Figs. 7, 8 and 9. In Fig. 7 400 is a frame to which is attached a contact bank 401 and a rewinding magnet 402. Bent round at right angles to the main surface of the frame, at the bottom transverse strip 403 thereof, are 25 two lugs 404, 405 to which is fixed by screws 406, 407 a disk 408 of agate or some other suitable semi-conductor. Contacting with the bottom of the semi-conductor disk 408 is a thin metal sheet 409. The disk 408 and 30 sheet 409 are electrically insulated from the frame 400 by bushings and washers of insulation surrounding the screws 406, 407 in the well known manner. Contacting with the top surface of the semi-conductor disk 35 408 is a metal disk 410 provided with a hemisphere 411 at the centre and a fork 412 near its periphery. The hemisphere 411 forms the convex part of a ball socket whose concave part 413 is fixed to a shaft 414. This 40 shaft is journaled in two bearings 415, 416 and the yielding connection formed by the ball socket 413, 411 between it and the disk 410 enables all parts of the contacting surface of the latter to always keep in intimate 45 contact with the top surface of the semi-conductor 408, independently of any slight lateral movements that the shaft 414 may execute in rotating the wipers 417, 418, 419, 420. These wipers are fixed on a bushing 421 and 50 electrically insulated therefrom. Also fixed on the bushing 421 and electrically connected with the wiper 420 is a bent arm 422 which carries the disk 410 around with it when the bushing 421 and the wipers are rotated by 55 the shaft 414. The bushing 421 is slightly longitudinally displaceable on the shaft 414, but is prevented from rotating relatively thereto by a pin 423 fixed in the shaft and 60 engaging with a slot 424 in the bottom of the bushing 421. The disk 410 is insulated from the shaft 414 by either the recessed block 413 or the hemisphere 411 being made of insulation. Slipped onto the shaft 414 is 65 a spring box 425 which is arranged to rotate relatively to the said shaft. The periphery

of the spring box 425 is connected to the shaft 414 by a clock spring. The shaft 414, disk 410 and wipers 417, 418, 419, 420 are normally turned into an initial position in which the wiper 420 engages with a bank 70 contact from which current flows through the wiper 420, arm 422, disk 410, stationary semi-conductor disk 408 and the metal sheet 409, so as to cause the disk 410 to adhere 75 strongly to the disk 408 and thus prevent rotation of the shaft and the wipers. With the shaft 414 thus fixed, the spring box 425 is rotated so as to tension the spring and provide a force that tends to rotate the shaft and the wipers. The spring box is held in 80 its tensioned position by a detent 426. If the current flowing through the disks 410, 408, 409 is now interrupted, the spring in the 85 spring box will whirl the shaft 414 and the wipers and disk 410 round in the direction of the arrow (Fig. 8) until the wiper 420 reaches a bank contact such as 427 connected to an electrical potential. The disk 410 will now again cleave to the surface of 408 and the wipers will be stopped. Subsequently 90 the spring in the spring box is retensioned by means of a stepping pawl 428 operated by a magnet 402. Attached to the top of the shaft is an arm 430 which is adapted to operate an off-normal contact 431 when the shaft 414 and the spring box 425 have regained their normal positions.

In Figs. 10, 11 and 12 the circuits of a line finder, group selector and connector respectively of the type shown in Figs. 7, 8 and 9 are illustrated. In these figures 408', 508 and 608 are the semi-conductor disks similar to the disk 408 of Figs. 7 and 9. 500, 501 and 600 are off-normal switches. 417', 418', 419', 420' are wipers corresponding to 100 wipers 417, 418, 419, 420 of Fig. 9. The group selector, Fig. 11, has five wipers 517, 518, 519, 520, 521 and the connector four wipers 617, 618, 619, 620 that wipe over rows of bank contacts. In the group selector 511 110 the bank contacts 502, 503, 504, 505, 506 are group designating contacts to which potentials are alternately applied by contacts 507, 509 of the line relay 510.

In the connector, 602, 603, 604, 605 are 115 group designating contacts and between these contacts line designating contacts such as 606, 607, 609, 610, 611, 612 are placed. Potentials are applied by contacts 613, 614 of the line relay 615 first alternately to successive group designating contacts and then to successive line designating contacts.

In the normal position the wipers of the line finder Fig. 10, are held by the adherence of the disk 410' to the semi-conductor disk 120 408', this adherence being caused by a current that flows from the positive pole through off-normal contact 530, metal sheet 531, disk 408', disk 410', 480² wiper 420', contact 532, wire 533, relay contact 535. 125

The wipers of the group selector, Fig. 11, are held in their normal position in a similar manner by a current that flows from the positive pole through off normal contact 536, 5 metal sheet 537, semi-conductor disk 508, metal disk 538, contact 539 of relay 540, wiper 521, bank contact 502, wire 541, contact 542 of release relay 543 to the negative pole. Similarly the wipers of the connector 10 are held in their normal position through a current flowing from the positive pole through off normal switch 630, metal sheet 631, semi-conductor disk 608, metal disk 632, wiper 620, bank contact 633, wire 634, contact 635 of release relay 636 to the negative pole.

The operation of the system will appear more fully from the following description of the events which occur in setting up a 20 connection between a calling and a wanted subscriber. It will be assumed that the subscriber, Fig. 10, desires a connection with number 113. He first raises his receiver, when a current flows from the positive pole 25 to the line relay 450, contact 451, line wire 452, station S, line wire 453, contact 454 of the cut-off relay 455 to the negative pole. The line relay closes its contacts 456 and 457, the latter contact applying a negative 30 potential to the stopping contact 458 of the line finder, while the contact 456 closes an energizing circuit through the relay 459 which is the common starting relay for a group of subscribers. When the relay 459 35 is thus energized, a starting impulse flows from the negative pole through 456, contact 460, armature 461, starting wire 462, off normal contact 463, relay 464 to the positive pole. The relay 464 is energized and at its 40 contact 535 opens the holding current which is normally closed through the semi-conductor 408', so that the tensioned spring of the finder whirls the wipers of the finder round until the wiper 420' reaches the 45 stopping contact 458, when a current again flows through the semi-conductor 408' from the negative pole through line relay contact 457, stopping bank contact 458, wiper 420', disk 410', semi-conductor 408', metal sheet 50 531, contact 465 of the relay 466 contact 476 to the positive pole. When the wipers are thus arrested a current flows from the negative pole through the contact 467 of the off normal switch 501, wire 468, relay 466, wiper 419', contact 469, cut off relay 455 55 to the positive pole. The cut off relay disconnects the line relay and the battery from the subscriber's line by contacts 451 and 454, and lowers the potential on the test wire 470 by cutting in more resistance or additional windings of the cut off relay through opening its contact 469. The relay 466 is thus energized to close its contacts 471, 472, 474 and open its contacts 465, 475. The positive 60 pole, which is taken off at contact 465, is,

however, kept connected to the metal plate 531 through the contact 476 of the relay 464 which closed a locking circuit for itself through its contact 477 and contact 478 of the release relay 543.

When the release relay 543 is energized as a result of the energization of the impulse relay 510 the locking circuit of the relay 464 is opened at 478, but at the same time a positive potential is applied through contact 480 and wire 481 to the plate 531 so as to keep the holding current for the wipers of the finder established through the semi-conductor 408'. The release relay 543 is energized by current from the negative pole through contact 479, wire 482, windings of release relay, resistance 483 to the positive pole, when the line relay 510 is energized by current from the positive pole through the left winding of the line relay 510, contact 484, trunk wire 485, 471, 417', 486, 453, calling station S, 452, 487, 418', 472, 488, 489, right hand winding of line relay 510 to the negative pole.

The starting wire 462 is extended through contact 490 of the off normal switch 500 to the next idle finder. This next finder cannot be started by current through the contact 456 of the line relay 450, because the negative pole connected through 456 to the wire 491 is disconnected at the contact 460 when the armature 461 is fully pulled up, so that before the off-normal contact 490 is closed by the wipers of the finder leaving their normal position the negative pole will be disconnected again from the wire 462. A new starting impulse cannot be sent through the wire 462 until the starting relay 459 is deenergized by the deenergization of the line relay 450, but as the wipers of the line finder reach the bank contact set of the calling line very quickly the interval during which a new starting impulse is incapable of being sent is very short.

When the calling subscriber S is connected through to the line relay 510 by the energization of the relay 466 as described the contact 509 is closed and the negative potential which is disconnected from wire 541 and the bank contact 502 of the group selector is applied through the contact 509. When the calling subscriber, who desires connection with a subscriber in the first hundred group, sends in one dialling impulse, i. e. causes an interruption and a subsequent closure of his line loop to take place, the armature 492 leaves contact 509 so as to disconnect negative potential from group designating contact 502 and connect this potential through contact 507 to the group designating contact 503. The holding current through 508 ceases to flow through contact 502 and the wipers are whirled round until the wiper 521 reaches contact 503. When the armature 492 leaves the contact 507, negative potential

is removed from the contact 503 and connected through contact 509 to the bank contact 504, so that the wiper 521 is turned forward until it reaches the contact 504. Thus the one dialling impulse, which resulted in the armature 402 being detracted and retracted, caused the wiper 521 to skip first a half step from the bank contact 502 to the contact 503 and then another half step from the latter contact to the contact 504. The wipers of the group selector are thus set onto the first group of sets of bank contacts that are connected to trunks leading to the first hundred group. During the oscillation of the armature of the line relay 510, the change-over relay 493 is energized by current from the negative pole through contact 494, 493, resistance 495, to the positive pole. When, after the wipers of the group selector have been set onto the desired group, the oscillations of the line relay armature cease the change-over relay 493 is short-circuited by the continued closure of the contact 496, so that the change-over relay 493 is deenergized to close its contact 497, whereby the relay 540 is energized by current from the positive pole through 540, 497, off normal contact 498 to the negative pole. The relay 540 closes a locking current for itself through its contact 499 and opens contact 539, while closing contact 550. The negative potential applied through 509, 541, wiper 521, contact 539 to metal disk 538 is thus taken off at contact 539 and the wipers are now whirled round until the wiper 520 encounters the bank contact such as 551 of a free trunk that is connected to the negative pole, when a current flows from the positive pole through 480, metal sheet 537, semi-conductor 508, metal disk 538, contact 550, contact 552, wiper 520, bank contact 551, wire 553, contact 640 of the release relay 636, Fig. 12 to the negative pole. The wipers of the group selector are thus arrested on the bank contacts 551, 554, 555, 556 of a free trunk and a current flows from the positive pole through the relay 450', wiper 519, bank contact 554, wire 557, off normal contact 641 to the negative pole. The relay 450', whose wiper 519 brushes over its bank contacts too swiftly to permit of its being energized by any live contact which it passes during its hunting operation, is now energized to close its contacts 451', 452', 453', 454' and open the contacts 484, 489 and 552. By closing the contact 451', the holding current through the semi-conductor 508 is maintained.

If all the trunks in the selected group are busy, the wipers of the group selector are arrested at the end of the group by means of a special stopping contact 460' which is permanently connected to the negative pole, and by which holding current is sent through the wiper 520, 552, 550 and the semi-conductor 508. The calling subscriber may be given a

signal by any suitable means which apprises him of the fact that the trunks in the wanted group are all busy and he thereupon replaces his receiver so as to deenergize the line relay 510 and short-circuit the release relay 543. When the release relay drops back, it opens at 470' the circuit of the relay 466, and at 471' it closes the circuit of the stepping or rewinding magnets 472' and 473' of the line finder and group selector respectively. The line finder rewinding magnet 472' receives current through 471', self-interrupter 474', 472', off normal contact 475', contact 475. The spring of the spring box first whirls the wipers of the line finder round until the wiper 420' reaches the normal contact 532, when the off normal contact 530 operated by the finder shaft is closed to establish the holding circuit through 535, 532, 408', 530 to the positive pole. The off normal contact 475' is kept closed until the spring box is turned into its normal rotary position relatively to the shaft and thus current flows from the negative pole through 471', 474' rewinding magnet 472', contact 475, contact 475 to the positive pole until the spring in the spring box is fully retensioned and the contact 475 is opened. When the release relay 543 is deenergized as described, negative potential is applied to the contact 502 through contact 542. The metal sheet 537 is, however, kept disconnected from the positive pole by the contact 536 until this contact is closed by the shaft of the switch rotating further round until the wiper 521 touches the contact 502. As the relay 540 is also deenergized when the release relay 543 drops back, a holding current will now flow from the positive pole through 536, 537, 508, 538, 539, 521, 502, 541, 542 to the negative pole. The rewinding magnet 473' receives current from the negative pole through 471', 473', self-interrupter 480', off normal contact 481' to the positive pole, until the off normal contact 481' is opened by the spring box reaching its rotary normal position relatively to the shaft of the group selector.

Assuming that the group selector has found a free trunk 553, 557, 558, 559, current will now flow through the line relay 615 over the calling line, and the line relay by its contact 645 energizes the release relay 636 by current through 636, resistance 646 to the positive pole. The release relay immediately establishes the busy condition of the seized trunk by removing negative potential from the test wire 553 by means of its contact 640. At the same time it closes, at contact 647, an additional path for energizing current through the relay 450' in the group selector. At 635 the release relay 636 disconnects negative potential from the wire 634 and the normal bank contact 633, so that the wipers are advanced a short distance,

until the wiper 620 strikes the bank contact 602, which is now connected to the negative pole through 648 and 613 of the line relay 615. When the wipers are moved out of their normal position, the off normal switches 600 and 649 are operated. If the calling subscriber now abandons the call by hanging up his receiver, the line relay 615 and the release relay 636 are both deenergized and the wipers are whirled further round, since negative potential is removed from the contact 602 at contact 613, until the wiper 620 reaches the bank contact 633, when the positive pole is connected through the off normal contact 630 to the metal sheet 631, and a stopping circuit for the wipers is thus closed through the semi-conductor 608. The stepping magnet or rewinding magnet 650 is energized through contact 651 of the release relay and through the second off-normal contact 652 which is controlled by the spring box of the selector. The stepping magnet or rewinding magnet 650 continues receiving current from the negative pole through contact 651', off normal contact 652, 650, self-interrupter 653 to the positive pole, until the spring box regains its rotary normal position relatively to the shaft of this connector. The contact 652 is then opened to deenergize the magnet 650. The deenergization of the release relay 636 also results in the opening, at contact 647, of the circuit of the relay 450' in the group selector, Fig. 11, so that relay 510 is deenergized by the opening of contact 484 and the group selector release relay 543 is short-circuited and applies negative potential through its contact 542 to the bank contact 502 while disconnecting positive potential at contact 480 from the bottom plate 537. The spring of the group selector now whirls the brushes round until they reach their normal position in which the brush 521 touches contact 502 and positive potential is reconnected through the off-normal contact 536 to the bottom plate 537. The brushes are then held against further rotary movement. The stepping magnet 473', whose circuit is closed at 471' when the release relay is deenergized, rewinds the spring box and when this box has regained its normal position relative to the brush shaft the second off-normal switch opens the rewinding magnet circuit at contact 481'. The deenergization of release relay 543 also causes the restoration of the line finder, Fig. 10, for when the contact 480 is opened positive potential is taken off the bottom plate 531 and simultaneously the relay 466 is deenergized by the opening of release relay contact 470'. The spring of the finder now whirls round the finder brushes until brush 420' strikes the normal bank contact 532 and a brush stopping current flows from the positive pole through the off-normal contact 530, plato 531, semi-conductor 408', brush 420', bank contact 532, contact 535 to the negative pole. The finder rewinding magnet 472' is energized when the release relay 542 is deenergized and it steps the spring box round until its circuit (negative pole 471', 474', 472', 475, 475', positive pole) is opened by the second off-normal switch 475 of the finder.

Assuming that the calling subscriber proceeds with the call, he will send in a tens dialling impulse and thus cause the armature 632 to execute one oscillation, whereby the negative potential is removed from the group designating bank contact 602 and placed on the group designating contact 603 through the back contact 614 and back contact 654 of relay 655, and then removed again from 603 and reconnected to the group designating contact 604. This causes the wiper 620 to be moved first from the bank contact 602 to 603 and then from 603 to 604, i. e. up to the desired group in the contact bank.

When the line relay 615 oscillates its armature in response to the tens dialling impulses, the change-over relay 660 is energized by current from the negative pole through 645, 660, 662 to the positive pole, but when the tens dialling impulses cease the change-over relay 660 is short-circuited by the contact 664 of the line relay, so that the contact 665 is closed to establish a circuit from the negative pole through 665, off normal contact 666, right hand winding of relay 655. This relay closes its contacts 667, 668, 669, 670 and opens contacts 648 and 654. At contact 668 the relay 655 closes a locking circuit for itself and at contact 667 it prepares a circuit for the busy tone relay 672. By opening contacts 648, 654 the relay 655 disconnects the contacts 613, 614 from the group designating bank contact of the connector and connects them through 669, 670 to the line designating bank contacts of the same. When the contact 648 is opened and the contact 670 closed, the negative potential applied through 613 is transferred from the group designating contact 604 to the line designating contact 673 and therefore the wiper 620 is moved to the contact 673. When the calling subscriber now sends in two units dialling impulses the negative potential is disconnected from contact 673 and applied to contact 674 and then reconnected to 675 during the first impulse, and then disconnected from the contact 675, connected to the bank contact 676 and reapplied to bank contact 677, during the second units dialling impulse. The wiper 620 is thus moved from contact to contact until it reaches the contact 677. During the sending in of the units dialling impulses the change-over relay 660 was again energized and opened its contacts 678, 679, while closing its contact 680. By 130

the latter contact it establishes an energizing circuit through 680, 667, relay 672 to the positive pole. This relay closes a locking circuit for itself at its contact 681 and prepares a path for the busy tone from the busy tone device 683. When the units impulses have all been sent in and the wipers of the connector have been set onto the set of bank contacts belonging to the wanted line, the change-over relay 660 is again short-circuited so that the contacts 678 and 679 are closed. Negative battery is connected through 678 to the test relay 686 and if the wanted line is free the test relay will be energized to immediately open the contact 687 and close its contacts 688, 689, 690 and 691. If the wanted line is busy the contact 687 will remain closed and a busy tone will be applied from 683 through 679, 682, 687, 692 to the calling line. The calling subscriber will then hang up his receiver and the switches will be restored in the manner already described.

Assuming that the wanted line is free and that the test relay 686 has been energized, the ringing relay 697 will be intermittently energized by current impulses from the positive pole through 698, 697, 691, 699 to the negative pole. The ringing generator 700 will thus send out ringing current impulses through contacts 701, 702. When the wanted subscriber responds the ringing cut off relay 703 is energized and the ringing current is cut off by the contact 699 being opened. The ringing cut off relay closes a locking circuit for itself by its contact 705.

The connector may be arranged to be restored to normal in any desired manner when the wanted subscriber hangs up.

In Figs. 7 and 9 a flexible connection between the wiper shaft and the contacting metal disk 410 is shown in the form of a ball socket 411 and a carrier 422 which carries the disk 410 around with it. A modified form of flexible connection is shown in Fig. 17. In this modified flexible mechanical connection the end of the shaft is tapered and rests in a flaring or conical cavity 800 in the disk 810. Carriers in the form of arms 822 are provided which are mechanically fixed, but electrically insulated from, the shaft 814. The ends 815 of these carriers 822 are forked and studs 816 fixed in the disk 810 extend between the prongs of the forks and transmit the rotary motion of the carrier 822 to the disk 810.

The semi-conductor 408 in Figs. 7 and 9 is fixed to the frame 400. It may, however, in some cases prove to be advantageous to provide automatically operating means for cleaning the top surface of the semi-conductor from time to time. Such automatic means are illustrated in Figs. 14 to 16. In these Figs. 408' is the semi-conductor, 410' the contacting metal disk, 412' the carrier

for carrying round the metal disk, and 413' the ball socket between the wiper shaft and the metal disk. The semi-conductor is mounted upon a bracket 900 which extends from a sleeve journaled on a vertical post 902. Attached to the sleeve 901 is a flexible disk 903 provided with a peripheral iron ring 904. Rotating near the metal ring 904 is an iron disk 905 which is arranged to be magnetized by a coil 906. When the revolving disk 905 is magnetized the ring 904 is attracted so that it is rotated to swing the sleeve 901 with the bracket 900 and the semi-conductor 408' mounted thereon round the pillar 902. The sleeve 901 carries a bent arm 910, at whose top end there is mounted a roller 911 of insulation. This roller, when the sleeve 901 is rotated in the direction of the arrow, bears against the lower surface of a contact spring 912 so that this spring is forced into contact with an upper spring 913. The springs 912 and 913 keep an energizing circuit of the coil 906 closed while the bracket 900 is swung round in the direction of the arrow. This circuit being initially closed by a contact of the switch at the moment it is released or restored to its normal position. When the roller 911 reaches the end of the inclined contact spring 912 this latter moves down away from spring 913. The energizing circuit through the coil 901 is thus opened and the driving disk 905 deenergized. A helical spring 914 now swings the bracket 900 back into its normal position shown in Fig. 14. During this restoring movement of the bracket 900 the roller 911 rides over the top surface of the spring 912 so as to prevent the energizing circuit of the coil 906 from being closed again. During these swinging movements of the bracket 900 with the semi-conductor disk 408' the latter moves past a brush 920 which cleans the top surface of the semi-conductor. The brush 920, which is shown in Fig. 14 in broken lines, is held by a bracket 921 attached to the pillar 902. The lower portion of the bracket 921 to which the brush 920 is attached is broken away in Fig. 14 so as to more clearly show the bent arm 910. The brush 920 is fixed between a bar 922, Fig. 16, and a strip 923 by means of screws 924. The brush 920 may consist of tufts of hair or of a strip of rubber.

When the bracket 900 is swung away from the metal disk 410' the latter is held suspended by loops or staples 925 which embrace the ends of the carriers 412'.

When the bracket 900 with the semi-conductor 408' is swung away from the disk 410' it is at first moved slightly downward so that, during the rest of its swinging movement, the top surface of the semi-conductor 408' is at a lower level than the bottom surface of a metal disk 410'. The said slight downward movement may be brought

about the part of the ring 904 that registers with the disk 905 when the ring 904 is in its normal position with a hump 930 so that the sleeve 901, in addition to being rotated by the disk 905, will also be pulled slightly downward. The downward movement may also be effected by a pin 931 projecting from the pillar 902 into a slot 932 in the sleeve 901, which latter slopes downward at its one end as shown in Fig. 14.

The current sent through the semi-conductor may be supplied from mains or a battery of higher potential than the current source used for the electromagnets and electromagnetic relays. The said battery of higher potential may be a battery of dry cells, because the current required for the semi-conductor circuit is very small.

Under certain conditions the idea underlying the present invention, viz. to obtain an extraordinarily sudden effect that will very abruptly stop travelling contacts on any desired relatively fixed contact, may be realized to a certain extent by employing an electromagnet whose armature is continually in direct contact with its pole, but which is only caused to adhere to the pole at proper moments by sending a current through its windings.

30 I claim:

1. A switch comprising bank contacts, brushes adapted to glide in a continuous motion over any desired number of said bank contacts, a continually acting power device tending to move said brushes, an arresting means both for holding the brushes in an initial position against the action of said power and for positively stopping the power-driven brushes on any desired bank contact.

2. A switch comprising bank contacts, brushes adapted to glide in a continuous motion over any desired number of said bank contacts, a continually acting power device tending to move said brushes, an arresting means for holding the brushes in an initial position against the action of said power device and for first positively stopping the power-driven brushes at a plurality of points arranged at certain distances apart and for then positively stopping the brushes after they have travelled a shorter distance than the distance between two said points.

3. A switch comprising bank contacts, brushes adapted to glide in a continuous motion over any desired number of said bank contacts, a continually acting power device tending to move said brushes, an arresting means for holding the brushes in an initial position against the action of said power device and for first positively stopping the power driven brushes at a plurality of points arranged at certain distances apart and for then positively stopping the

brushes at a plurality of other points placed closer together than the said first points.

4. A switch comprising bank contacts, rotary brushes adapted to glide in a continuous motion over any desired number of said bank contacts, a continually acting power device tending to move said brushes, an arresting means for holding the brushes in an initial position against the action of said power device, for positively stopping the power-driven brushes on any desired bank contact and for finally stopping the brushes again in their initial position.

5. In a switch, bank contacts, a wiper cooperating with the bank contacts, a wiper carrier, a metal surface moving together with the wiper carrier, a semi-conductor bearing against the said metal surface, and an electric circuit for affecting the adhesion between the said metal surface and semi-conductor, the said circuit including the said surface and semi-conductor.

6. In a switch, bank contacts, a wiper cooperating with the bank contacts, a wiper carrier, a metal surface moving together with the wiper carrier, a continuously acting power device for driving the said carrier, a semi-conductor bearing against the said metal surface, and an electric circuit for affecting the adhesion between the said metal surface and semi-conductor.

7. In an automatic telephone switch, bank contacts, a set of wipers cooperating with the bank contacts, a wiper carrier, a metal surface moving together with the wiper carrier, a semi-conductor bearing against the said metal surface, and an electric circuit for affecting the adhesion between the said metal surface and semi-conductor, the said circuit including the said surface, semi-conductor, wiper and a said bank contact.

8. A switch comprising bank contacts, rotary brushes adapted to glide in a continuous motion over any desired number of said bank contacts, a continually acting power device tending to move said brushes, an arresting means for holding the brushes in an initial position against the action of said power device and for first positively stopping the power-driven brushes at a plurality of points arranged at certain distances apart and for then positively stopping the brushes after they have travelled a shorter distance than the distance between two said points and for subsequently stopping the brushes again in their initial position.

9. A switch comprising bank contacts, rotary brushes adapted to glide in a continuous motion over any desired number of said bank contacts, a continually acting power device tending to move said brushes, an arresting means for holding the brushes in an initial position against the action of said power device and for first positively stop-

ping the power-driven brushes at a plurality of points arranged at certain distances apart and for then positively stopping the brushes at a plurality of other points placed closer together than the said first points and for subsequently stopping the brushes again in their initial position.

10. A switch comprising bank contacts, a brush carrier with brushes adapted to glide in continuous motion over any desired number of said bank contacts, a continually acting power device tending to move said brush carrier, two conducting parts in contact with

each other one of which is a semi-conductor, and one of which is fixed to the brush carrier 15 while the other is held stationary, electric circuits co-operating with said conducting parts; said circuits and conducting parts forming an arresting means for holding the brushes in an initial position against the 20 action of said power device and for positively stopping the power-driven brushes on any desired bank contact.

In testimony whereof I have signed this specification.

FRITZ ALDENDORFF.
